UNITED STATES PATENT OFFICE.

HERBERT E. IVES, OF MONTCLAIR, NEW JERSEY, ASSIGNOR TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed September 24, 1924. Serial No. 739,525.

This invention relates to the transmission of pictures, writing, etc., by electricity and, more especially, it relates to a novel arrangement for reproducing a picture particularly 5 suitable for printing by the stereotype process.

In a copending application of H. E. Ives, Serial No. 711,755, filed May 8, 1924, a system for effecting the transmission of pictures by electricity in an efficient and practical manner is disclosed. According to this 10 system, the characteristics of the picture are transmitted as impulses of a voice frequency carrier wave especially adaptable to transmission over ordinary telephone lines or circuits. The modulated waves are received at a distant station and effect the operation 15 of a light controlling valve which causes the exposure of a photosensitive surface in accordance with the tone value of elemental areas of the picture. The picture is thus reproduced on this sensitive surface in the form of a plurality of parallel lines of uniform density and varying width. In the 20 reproduction of pictures suitable for news print work, it is necessary, even in the totally white areas of the picture, to provide a printing structure. This, according to the invention covered in the previously referred 25 to application, results from the formation of thin, narrow lines over such areas. However, when such pictures are reproduced on news print paper by the stereotype process, these thin lines are frequently so broadened 30 that the white portions of the picture appear too gray and the reproduced picture consequently lacks contrast.

It is the principal object of the present invention to accomplish the transmission of 40 pictures by electricity in a practical manner and effect the reproduction of the pictures in a form especially suitable for news print reproductions.

In one embodiment of the invention, the 45 characteristics of the picture, which are transmitted as impulses of a voice frequency current wave to a distant station over ordinary telephone lines, are reproduced at the distant station on a photosensitive surface 50 not as continuous parallel lines of uniform density and varying width, but as broken lines of uniform density and varying width. Between the breaks in the lines dots of pre- 55 arranged dimensions are formed automatically, thereby providing a structure which is

particularly adapted to news print work. These dots appear only in the portions of the picture representing light areas, for in the other areas they are submerged by the lines. Such an arrangement gives a more 60 faithful reproduction since it produces greater contrast between the white or light and dark areas.

A better understanding of the invention may be had from the following description, 65 taken in conjunction with the accompanying drawing consisting of the following figures: Fig. 1 shows diagrammatically the apparatus and circuits located at the transmitting terminal station; Fig. 2 illustrates dia- 70 grammatically the apparatus and circuits located at the receiving terminal for reproducing the characteristics of the picture as transmitted through the apparatus and circuits of Fig. 1; Fig. 3 shows a printing 75 structure of a picture as reproduced by the method disclosed in the previously referred to application; Fig. 4 shows the printing structure produced in accordance with the embodiment of the present invention. 80

Referring for a moment to Fig. 1, a modulator 13 is supplied with carrier waves from an alternating current source 12 and with picture current from a photo-electric cell 8 and a picture amplifier 2. Modulated carrier waves from the modulator 13 are impressed upon the transmission line 14 which extends between two remotely situated stations through a filter SPF. The photo-electric cell 8 is located within a transparent 90 drum 4 which is driven in any suitable manner by shaft 3 to which power is communicated. Mounted on the drum 4 is a transparency 5 of the picture, the characteristics of which are to be transmitted. Light from an incandescent source 6 is focused by means of a lens 7 on the photo-electric cell 8 through an aperture in a screen 1. The amount of light affecting the photo-electric cell 8 is determined by the tone value or density of the elemental area of the transparency 5 which is, at that instant, adjacent to the aperture in the screen 1 at the focal point of the light beam. The amount of light within the photo-electric cell 8 in turn 95 determines the amount of current which can flow from the battery 9 to the photo-electric cell 8 and resistance 10. Consequently, the potential drop across the resistance 10 is applied to the input circuit of the picture am- 100 105 110

plifier 2. The amplified current determined by the amount of light affecting the photo-electric cell 8 is impressed upon the modulator 13 by resistance 11 simultaneously with carrier current from the current source 12. Accordingly, modulated current waves from the modulator 13 are impressed upon the line 14 through the filter SPF.

Coming now to the receiving arrangement shown in Fig. 2; the modulated carrier waves from the line 14, after passing through the filter RPF, are impressed on an amplifier set RA and thence to the operating wire 18 of a light valve 16 through a suitable transformer 15. The operating wire 18 is suspended in a magnetic field produced by magnet 19 and is arranged to vibrate in a direction transverse to the plane of the paper. For further details with reference to the construction and character of operation of the light valve 16, reference should be had to copending application of E. C. Wente filed May 1, 1923, Serial No. 635,886.

Light from the source 20 is directed by means of lens 21 upon the conductor 18. Preferably, the light source 20 is an incandescent lamp with spiral filaments arranged coaxially with the lens 21 so that the aperture forming elements of the light valve 16 are intensely and uniformly illuminated. The operating conductor 18 is one of these aperture forming elements. The screen 25 is another. It is, of course, understood that these members or elements may be so located as to produce a no exposure condition.

Light from the source 20 in turn controlled by the light valve 16 passes through a lens 22 and exposes a photosensitive surface 24 carried by a drum 23. The drum 23, like the drum 4 located at the transmitting station, is adapted to be rotated for bringing the various elemental areas of the photosensitive surface 24 in alignment with the image of the aperture in screen 25. Interposed between the light valve 16 and the lens 22 is a transparent mirror 26 which allows the passage of the light rays from the source 20 as determined by the operation of the light valve 16. Arranged in operative relation with respect to the transparent mirror 26 is an auxiliary light source 27 of the same character as the light source 20. Light beams from the light source 27 are directed on the mirror 26 through a lens 28 and a screen 29, in which is an aperture whose optical distance from the drum 23 is the same as that of the aperture in screen 25. Located adjacent to the screen 29 is a sectored disc 30 which functions to break up the light impressed from the light source 27 on the transparent mirror 26 and, in consequence, the photosensitive surface 24.

The photosensitive surface 24 is such that it is exposed to full depth by a single exposure to light from either light source 20 or

light source 27. Additional exposures of the same area have no effect to change this tone value. Thus, the developed record possesses only two tone values, one corresponding to exposure and the other corresponding to no exposure.

According to the preferred form of the invention, the characteristics of the picture transmitted are reproduced as lines of uniform density and varying width. In place of having the white areas of the picture represented by a fine narrow line of uniform density for providing a printing structure, dots are produced which not only provide the necessary printing structure but which also give more contrast between the white and dark areas. It is, therefore, intended that the currents produced by the operation of the photo-electric cell 8 in accordance with the elemental tone value or density of the transparency 5 be so adjusted that for practically white areas no current be impressed on the modulator 13. Thus, at the receiving station, the light valve 16 will be closed and, consequently, no light is impressed on the photosensitive surface 24 from the light source 20. During this period, however, light from the auxiliary source 27 is applied through the sectored disc 30 and reflected by the transparent mirror 26 to the photosensitive surface 24. The exposure of the photosensitive surface due to the use of the sectored disc 30, results in a series of images of the aperture in screen 29, forming dots of uniform size and density as shown in Fig. 4. By omitting the sector disc 30, the auxiliary source of light 27 may be made to expose the photosensitive surface to produce a thin narrow line which may be sufficient for certain purposes.

For the transmission of pictures, the arrangements of Figs. 1 and 2 are connected by the telephone line 14. The drums 4 and 23, located at the transmitting and receiving stations respectively, are adapted to be maintained in synchronism by any suitable arrangement, such, for example, as that shown in the copending application of M. B. Long, Serial No. 681,347, filed December 18, 1923. As the drum 4 rotates, a carrier current, modulated in accordance with the elemental tone value or density of the successive areas of the transparency 5, is transmitted over line 14 and impressed in amplified form upon the operating wire 18 of the light valve 16. The light valve 16 is operated in accordance with the impressed currents for allowing light from the light source 20 to expose the photosensitive surface 24 in accordance with the elemental tone value or density of the transparency 5. In the case of white areas appearing in the transparency 5, the current is so adjusted that the light valve 16 is maintained closed when the photo-electric cell 8 is adjacent

to these areas. The photosensitive surface 24 will, however, be exposed to reproduce dots in the form shown in Fig. 4 due to the application of light through the sectored disc 30 and the transparent mirror 26 from the light source 27. The photosensitive surface will, thus, be exposed, but the dots produced by the sectored disc 30 will be submerged by the lines whenever the width 10 of the line is greater than the size of the dots.

The invention has been shown and described as applied to a particular system, but it is obvious that it may be applied to other systems with equally good results. It is, therefore, not intended that the invention should be limited to the particular arrangement disclosed.

What is claimed is:

1. In a system for transmission of pictures by electricity, means to modulate a carrier wave in accordance with the tone value of the elemental areas of the picture, a light controlling valve, means to impress said modulated current on said light controlling valve, a photosensitive surface exposed in accordance with the tone values of the elemental areas of said picture as determined by the operation of said light controlling valve, an auxiliary optical system for exposing said photosensitive surface to produce dots in the white areas comprising a transparent mirror through which light rays controlled by said light controlling valve pass, the auxiliary source of light reflected by said mirror on said photosensitive surface, and means for breaking said light up into dots.

2. In a system for transmission of pictures by electricity, means to modulate a carrier wave in accordance with the tone value of the elemental areas of the picture, a light controlling valve, means to impress said modulated current on said light controlling valve, a photosensitive surface exposed in accordance with the tone values of the elemental areas of said picture as determined by the operation of said light controlling valve, an auxiliary optical system for ex-

posing said photosensitive surface to produce dots in the white areas comprising a transparent mirror through which light rays controlled by said light controlling valve pass, the auxiliary source of light reflected by said mirror on said photosensitive surface, and a sectored disc for breaking up said light 55 into dots.

3. In a system for the transmission of pictures by electricity, a reproducing element, a transparent mirror, a source for producing a beam of light, means for directing the beam of light through said mirror to the surface of said element, a light valve actuated in accordance with the transmitted picture currents for controlling said beam of light to expose the reproducing element in 60 accordance with the tone values of the original picture, a second source of light, means for directing a beam from said second source to the surface of the mirror, said mirror serving to reflect said second beam to 70 the surface of said element, and means for controlling said second beam in such a manner that a uniform dot pattern is secured throughout the area of said reproducing element. 75

4. In a system for the transmission of pictures by electricity, a sensitized reproducing element, a source for producing a beam of light, a stationary transparent mirror, lenses for directing said beam through said mirror 80 and to the surface of said element, a light valve responsive to picture currents for controlling said beam to reproduce the tone values of the picture on said element, a second source for producing a beam of light, 85 means for directing said second beam to the surface of said mirror, said mirror serving to reflect the second beam to the surface of said element, and a rotating disc acting upon said second beam to cause a uniform dot 90 pattern to be superposed upon said reproducing element.

In witness whereof, I hereunto subscribe my name this 18th day of September, A. D. 1924.

HERBERT E. IVES.
